CLAIM

The ornamental design for a motor vehicle, toy or replica thereof, as shown and described.

DESCRIPTION

FIG. 1 is a front, right side perspective view of the motor vehicle, toy or replica thereof of the present invention with the convertible top closed;

FIG. 2 is a rear, left side perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a front, right side perspective view thereof with the convertible top open;

FIG. 10 is a rear, left side perspective view thereof;

FIG. 11 is a front view thereof;

FIG. 12 is a rear view thereof;

FIG. 13 is a right side view thereof;

FIG. 14 is a left side view thereof; and,

FIG. 15 is a top view thereof.

The evenly-broken lines are included for the purpose of illustrating portions of the motor vehicle, toy and replicas thereof that form no part of the claimed design. The unevenly-broken lines illustrate boundaries of the claim.

1 Claim, 8 Drawing Sheets
